Primary Examiner — Celia Murphy*Assistant Examiner* — Clare Ann Gannon(74) *Attorney, Agent, or Firm* — Polsinelli PC(57) **CLAIM**

The ornamental design for a memorial book, as shown and described.

DESCRIPTION

FIG. 1 is a perspective view of a memorial book showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded perspective view thereof; shown in an opened position.

The broken lines showing hinges in FIGS. 2-4; 6 and 7; and an internal block in FIG. 8, are included for the purpose of illustrating portions of the memorial book that form no part of the claimed design.
